UNITED STATES PATENT OFFICE.

FRED LACEY, OF ADAMS, MASSACHUSETTS.

SHEDDING MECHANISM FOR LOOMS.

SPECIFICATION forming part of Letters Patent No. 484,326, dated October 11, 1892.

Application filed September 23, 1891. Serial No. 406,599. (No model.)

To all whom it may concern:

Be it known that I, FRED LACEY, a citizen of the United States, residing at Adams, in the county of Berkshire and State of Massachusetts, have invented certain new and useful Improvements in Shedding Mechanism for Looms, of which the following is a specification, reference being had therein to the accompanying drawings.

- 10 My invention relates to shedding mechanisms for looms and in particular to what are known as "dobbies." Shedding mechanisms for looms may be divided into two general classes—namely, those which are known as 15 "close shed" and those which are known as "open shed." In the class first mentioned each shed in the warp is formed by moving warp-threads out of the normal plane of the warp-threads in the loom, all of the threads 20 thus moved out of the said plane being returned thereto after a pick of weft-thread has been introduced and prior to the formation of a new shed for the reception of the next weft-thread. In the other class, if certain of 25 the warp-threads are to appear on the same side of the weft-thread for two or more consecutive picks, such warp-threads will be caused to remain in the position into which they were at first moved until after all of such 30 picks have been introduced. It is found desirable to employ open-shed harness-operating mechanism in weaving certain materials and when it is desired to produce certain fabrics, while the use of close-shed harness-oper- 35 ating mechanism is deemed best in the case of others. There is in use at the present time a form of open-shed dobby, in which each of the harness-levers has pivoted thereto a lever, this latter lever being sometimes termed a 40 "connector." Hooked jacks, which are pivoted to the opposite ends of this connector, extend outward horizontally from the connector, one jack at a distance above the other, and beneath each horizontal series of the 45 jacks pertaining to the series of harness-levers employed in the loom plays a horizontally-reciprocating bar called a "lifter," the jacks being under the control of a pattern-chain and intermediate connections, by means 50 of which the jacks may be either lifted out of position to be engaged by the lifters or may be dropped into position to be engaged there-

by. The lifters alternate in their reciprocations, one thereof moving outward as the other moves inward, and one or the other of the two lifters moves outward prior to each pick of the loom. When in their normal inner position with the jacks disengaged from the lifters and the harness-frames in their depressed normal position, both ends of the connectors rest against fixed back-stop bars. If now either of the jacks pivoted to a connector is permitted to become engaged with a lifter as the said lifter moves outward just prior to a pick, the corresponding end of the connector will be moved outward and the connector will turn, as on a pivot, on that portion of the other end which rests against the corresponding back-stop bar, the harness-lever and harness-frame being changed in position in consequence of the movement of the connector. When the lifter just referred to moves inward after the said pick and prior to the next pick, the jack and corresponding end of the connector to which it is pivoted also move inward and the harness-lever and connected harness-frame return to their original positions unless the other jack pivoted to the connector is permitted to become engaged by the other lifter, in which event the harness-lever and harness-frame are held from returning to their original positions and the warp-threads controlled by the said harness-frame appear on the same side of the weft at the next pick of the latter. In this case, as the first jack moves inward with its lifter the other jack moves outward with its lifter, and the result is that the connector simply is swung on the pivot which joins it to the harness-lever, while the harness-lever, harness-frame, and the connected warp-threads remain in the position into which they formerly were moved—namely, that for the open shed. This form of dobby is a general favorite, and great numbers of such dobbies have been applied to looms; but, as ordinarily constructed and arranged, it is unfit for doing work of the close-shed character, because of the impossibility of causing a harness-frame which has been raised for one pick of weft to return to the close-shed position and then rise again prior to the succeeding pick. Heretofore when a mill has had the looms therein equipped with open-shed dob-

bies like that just described, and of the usual construction, and it has been desired to fit the said looms for the production of fabrics in which the weaving should be effected in 5 whole or in part on the close-shed principle considerable expense has been involved. The object of my invention is to avoid this expense by rendering open-shed dobbies, such as that just described, capable of working on 10 both the open-shed principle and the close-shed principle, and also to fit them for a more widely-extended range of use than heretofore.

My invention consists in certain improvements in a dobby of the general character of 15 that which has been described and will first be described in connection with the illustration thereof in the accompanying drawings, and then will be particularly pointed out in the claim at the close of this specification.

20 In the drawings, Figure 1 is a view in elevation of portion of a loom, showing my invention applied thereto. Fig. 2 is a view in vertical section of a part of the devices shown in Fig. 1; and Fig. 3 is a view of a portion of 25 a pattern-chain, illustrating the manner in which the pegs or pins are to be arranged thereon.

Certain of the parts shown in the drawings, as will be understood, are such as have heretofore been employed in looms and the dobbies usually applied thereto. These parts 30 may be described, briefly, as follows.

A is the loom-frame. B is the crauk-shaft of the loom mounted in the said frame.

35 C are the harness-frames of the loom. D are the harness-levers, to which the harness-frames are connected by cording E, and F are pulleys or sheaves around which the cording passes. In what are known as "spring-dobbies" the cording E is interposed only between the upper ends of the harness-levers and the upper sides of the harness-frames, and springs (not herein shown) are employed to draw down the harness-frames after the latter have been lifted, these springs being connected with the under sides of the harness-frames. In what is known as a "positive dobby," which is the variety I have chosen to illustrate, the cording is connected with 40 both the upper and the lower sides of the harness-frames and with the opposite ends of the harness-levers, as shown in Fig. 1 of the drawings, and the harness-levers are actuated in such a manner as to move the harness-frames positively in both directions, the 45 springs being omitted.

D' is the rod on which the harness-levers are pivotally mounted.

d are the connectors pivotally mounted on 50 the harness-levers.

P are the back-stop bars against which the upper and lower ends of the connectors rest normally.

e are the hooked jacks pivoted to the opposite ends of the connectors.

a are the lifters moving in slots g in the frame of the dobby.

b² are rods connecting the ends of the lifters with the opposite extremities of the arms H, mounted at both ends of the rock-shaft I. 70

h are the vertical needles or wires, upon the upper ends of which the upper series of jacks rests, and l are the pattern-levers or indicator-fingers pivotally mounted on rod l' and having upturned inner extremities, of which extremities those marked i act directly against the under sides of the jacks of the lower series, these jacks resting on said extremities, while the extremities marked k support the lower end of the vertical wires or needles h. The weighted ends of the pattern-levers l overhang a pattern-barrel n and are acted upon, as usual, by pegs or pins o, inserted into holes n' in the bars of the pattern-chain m, the said pattern-barrel n being provided with a ratchet-wheel n¹², which is engaged by the pawl i', connected with one end of one of the levers or arms H, the pattern-barrel being given thereby a movement forward of one step at each inward movement of the lower lifter. 80

The parts of the dobby as thus far described, when combined with means for imparting an oscillating motion to the rock-shaft I, constitute all that it is usual to employ in a spring-dobby. In a positive dobby there are combined with the foregoing check-bars O O, which are notched or rabbeted on their under sides and disposed on the frame of the dobby adjacent to the free ends 95 of the hooked jacks, above such free ends, and in position to be engaged by the latter when the pattern connections operate to lift the jacks out of position to become engaged by the lifters, in order that the jacks thus lifted may be prevented from having any unintentional outward movement whatever; also, the depressors f f are provided, these being placed in inclined slots g' g' in the dobby-frame adjacent to the upper and lower ends 100 of the connectors d and being connected at their ends by the rods c c to the ends of the lifters. These depressors thereby are caused to move with the adjacent lifters and in the same direction therewith, respectively, and in 105 operation they act, respectively, as the corresponding lifters move inward to carry inward positively the adjacent ends of the connectors which were moved outward in the last outward movement of the lifters. 110

115 There is nothing new in either the spring-dobby or the positive dobby, so far as described. In the ordinary dobby the rock-shaft I is actuated and the dobby thereby is operated through an arm K thereon, which is connected by a rod L with the operative mechanism of the loom to which the dobby is applied. Usually the said rod is connected with a crank or other device whereby the rock-shaft is given one complete oscillation or reciprocation for 120 each two picks of the loom. The result of this is that one lifter moves outward at one pick of the loom simultaneously with the inward movement of the other lifter, and the lat-

ter lifter moves outward at the next pick simultaneously with the inward movement of the first lifter. In consequence the dobby is operative only on the open-shed principle, because there is no provision whereby a harness-frame that has been raised during the outward movement of a lifter for one pick can be returned to its normal position and raised again prior to the succeeding pick, as is required in close-shed weaving when the same warp-threads are to be lifted for successive sheds. In furtherance of my present invention and with the object in view of rendering the dobby operative on the close-shed principle I connect the rod L with a crank-pin M on a disk N, carried by the crank-shaft B of the loom, or by equivalent means I actuate the said rods with such speed and timing as to secure a complete oscillation of the rock-shaft I and a complete reciprocation of each of the lifters for every rotation of the crank-shaft, and consequently for every pick of the loom. It is to be understood that I am aware that it is not new, broadly, to operate the rock-shaft I with such timing as to occasion a complete reciprocation thereof at every rotation of the crank-shaft. This has been proposed before, and, also, in the endeavor to fit a dobby for close-shed weaving. However, in the only case at present known to me in which a dobby has been adapted for close-shed weaving the connections intermediate the rock-shaft and one of the lifters and its connected depressor have been modified, so that the movements of the said lifter and depressor have been reduced one-half, and in addition the hooked jacks co-operating with such lifter have been freed from the control of the pattern devices and locked in engagement with the lifter. Thereby the said lifter and its connected depressor have been made operative to raise from the bottom portion of each shed to the central or closed plane of the shed just prior to the opening of a new shed the warp-threads of all the harness-frames which were left down at the opening of the shed immediately preceding and afterward to depress the harness-frames which are not lifted in the formation of the said new shed, the work of lifting the harness-frames to carry the warp-threads thereof to the top plane of each shed in the order dictated by the pattern and of afterward depressing them to the normal plane devolving upon the other lifter and its depressor.

By my invention, as will hereinafter be made to appear, I enable a dobby to be employed for close-shed weaving without any change being made in the mode of operation of the lifters and depressors or other essential parts thereof or any change being made in the actuating connections of the lifters and depressors. I also fit the dobby for being employed in the production of fabrics where in one part is woven on the close-shed principle and another part is woven on the open-shed principle, the two parts being woven

simultaneously or successively, as desired. I secure all these results by providing means for operating the shaft I with the timing described and by employing an arrangement of parts for controlling the jacks, in which, as shown in Fig. 2 of the drawings, a separate indicator-finger or pattern-lever l is employed for each individual jack of both horizontal series of jacks, and the pattern-chain has for each finger or lever l a line of perforations, into which pins are inserted as required. The jacks of both series of jacks are thus individually and independently controlled by the pattern-chain, whereas, usually, both of the jacks, connected with a connector, are under the control of one and the same indicator-finger or pattern-lever. There being two independent indicator fingers or levers for each harness-lever, one of such levers controlling the jack which is pivoted to the upper end of the connector for the said harness-lever and the other controlling the jack which is pivoted to the lower end of the said connector, either of the lifters, when desired, or both in succession, may be made to act in moving the harness-lever and raising the harness-frame. How this enables me to secure the desired results will be readily understood from the following. In consequence of actuating the rock-shaft I in a manner to occasion a complete oscillation of the same for each rotation of the crank-shaft of the loom one of the lifters will be moved outward just prior to the first throw of the shuttle and inward right after said throw, while the other lifter will make its outward movement simultaneously with the inward movement of the first lifter, this outward movement and the return of the second lifter occurring between two successive throws of the shuttle, and it will be obvious that the sheds in the warp-threads for the reception of the weft-thread must, inasmuch as it is the only one which is so timed in its movements as to be in its outer position at the time the shuttle is thrown, be formed through the action of the lifter first mentioned. For operating a harness-frame in the manner required for close-shed weaving the pins or pegs of the pattern-chain will be so placed on the successive bars of the chain as to act only upon the indicator or pattern lever or finger which controls the jack engaging with the said lifter first mentioned, and in consequence the other lifter will move to and fro without engaging with the other of the jacks belonging to the said harness-frame. It will be obvious that a jack whenever engaged by the first lifter will be drawn outward thereby prior to one pick and will be permitted to move inward immediately after that pick and before the formation of the next shed is begun. For operating a harness-frame in the manner required for open-shed weaving the pins or pegs of the pattern-chain will be so placed on the successive bars of the chain as to act upon both of the indicator or pattern levers or fin-

gers which control the jacks pertaining to the harness-frame at those times when the said harness-frame is to be held elevated continuously. Thereby both of the jacks may be permitted to fall into position to engage with the lifters, and in this event each lifter in turn will become operative to lift or maintain lifted the particular harness-frame which may be held up through as many picks as may be required. By suitably disposing the pins or pegs in the holes of the pattern-chain a harness-frame may be operated at one time as required for close-shed weaving and another time as required in open-shed weaving, or while one harness-frame or series of harness-frames in a loom are being operated as required in close-shed weaving another harness-frame or set of harness-frames in the same loom may be operated as required for open-shed weaving.

In Fig. 3 of the drawings I have shown how the pins or pegs may be placed in the holes of the bars of a pattern-chain for securing the desired mode of operation of the harness-frames. At the right-hand side of the dotted line α in the said figure I have represented by black dots the positions of the pins or pegs as required for close-shed weaving, while at the left-hand side of the said line I have represented the positions of the pins or pegs as required for open-shed weaving.

In the accompanying drawings I have represented all the pins or pegs for a single pick applied to a single bar of the pattern-chain and the pattern-chain as being moved forward one bar at each pick of the loom. The said pins or pegs, however, may be divided between two successive bars, and in this case the pattern-chain will be advanced one step prior to the outward movement of each lifter or twice for each pick.

A practical weaver will see that my invention is particularly serviceable in the production of a fabric wherein the effects due to different weaves and modes of weaving should appear in stripes side by side.

My invention is of particular service in cross-weaving. Heretofore in such weaving, when dobbies have been employed, it has been necessary usually to employ special constructions and arrangements of parts for the

purpose of lifting or easing up the warp-threads under which the doups are caused to pass, and thereby facilitating the movements of the doups and of the crossing warp-threads.

When using a dobby to which my invention has been applied, no change or addition is necessary when it is desired to do cross-weaving. All that is required is to arrange the pins or pegs in the bars of the pattern-chain in a manner similar to that in which they are arranged for close-shed weaving.

I claim as my invention—

1. In a loom, a series of harness-frames, harness-levers, cording connecting said harness-frames with said harness-levers, a pair of hooked jacks operatively connected to each of said levers, two lifters to engage with the hooks of the said hooked jacks, operating devices for giving to each of the said lifters a full forward and return motion for every revolution of the crank-shaft of the loom, pattern-indicating bars, means for moving the same, and two indicating-fingers for each harness-lever, operated upon by the pattern-bars, all combined substantially as described.

2. In a loom, a series of harness-frames, harness-levers, cording connecting said harness-frames with said harness-levers, a pair of hooked jacks operatively connected to each of said levers, two lifters for engaging with the hooks of the said hooked jacks, operating devices for giving to each of said lifters a full forward and return motion for every revolution of the crank-shaft of the loom, pattern-indicating bars having each pick doubly indicated for open-shed formation and each pick singly indicated for close-shed formation, means for moving said bars, and two indicating-fingers for each harness-lever operated upon by the pattern-bars, all combined and adapted to operate on both the open-shed principle and the close-shed principle at the same pick of the loom, substantially as described.

In testimony whereof I affix my signature in presence of two witnesses.

FRED LACEY.
